ATTORNEY.

UNITED STATES PATENT OFFICE

ARTHUR J. LAYHON, OF LOWELL, MASSACHUSETTS, ASSIGNOR OF ONE-HALF TO
REUBEN DUNSFORD, OF CHELMSFORD, MASSACHUSETTS

WRENCH

Application filed June 3, 1929. Serial No. 368,120.

This invention relates to a wrench of the ratchet type and has for its primary object to provide, in a manner as hereinafter set forth, a wrench of such type including as a part thereof a reciprocal element adapted to frictionally engage an object to which the wrench is applied when the latter is actuated in one direction and to release the object when the wrench is actuated in the opposite direction.

A further object of the invention is to provide a wrench of the type aforesaid which is of simple and durable construction, positive and efficient in operation, and which may be economically manufactured.

With the foregoing and other objects in view, the invention consists of the novel construction, combination and arrangement of parts as hereinafter more particularly described, and as illustrated in the accompanying drawings wherein are shown several embodiments of the invention, but it is to be understood that the description and drawings are to be taken as illustrative and that the invention is intended to be limited only by the scope of the claim hereunto appended.

In the accompanying drawings in which like numerals are employed to designate like parts throughout the same:

Figure 1 is a top plan of a wrench in accordance with this invention.

Figure 2 is a longitudinal section thereof.

Figure 3 is a section taken on line 3-3 of Figure 1.

Figure 4 is a section taken on the line 4-4 of Figure 1.

Figure 5 is a perspective view showing the engaging and releasing positions of the nut engaging element in the operation of the wrench.

Figure 6 is a bottom plan of a modified form of wrench.

Figure 7 is an elevation of the form shown in Figure 6.

Figure 8 is a top plan of a further modified form of wrench.

Figure 9 is an elevation of the form shown in Figure 8.

Referring to the drawings in detail, the numeral 1 indicates the body portion of my

improved wrench which is of elongated form and provided adjacent its ends with circular openings 2 and 3 respectively. Formed in the wall of the opening 2, adjacent the innermost extremity of the latter, is a recess 4 which is of elongated formation and which gradually decreases in width from its outer end to its inner end with respect to the body portion 1. The inner end 5 of the recess 4 is located substantially midway between the sides of the body portion 1. A similar recess 6 is formed in the wall of the opening 3, adjacent the innermost extremity of the latter.

Fixedly secured to the body portion 1, by means of a suitable staple 7, is an elongated tension element 8, the ends of which are offset at right angles to provide noses 9 and 10 respectively. The nose 9 extends transversely of the body portion through the recess 4 and the nose 10 extends transversely of the body portion through the recess 6.

The element 8 is formed of resilient material and is flattened for a portion of its length on either side of the steeple 7 to increase the resiliency of the element 8. The flattened portions are indicated at 11. The tension element 8 is so disposed as to normally maintain the noses 9 and 10 at the inner ends of the recesses 4 and 6 respectively. The flattened portions 11 are disposed with their narrower dimensions extending in the direction of travel of the noses and with their wider dimensions extending at right angles to the narrower dimensions.

In the embodiment illustrated in Figures 6 and 7 the body portion 12 is formed at one end with a circular opening 13, the wall of which is provided with a recess 14 which is similar to the recesses 4 and 6 heretofore described. In this form, the tension element 15 is in the form of an arcuate rod, one end of which is right angularly offset for extension through the body portion 12 whereby the rod is pivotally connected with the body portion. The free end of the offset portion is upset as indicated at 16 for maintaining the rod and body portion in assembled relation. The opposite end of the rod 15 is right angularly offset to provide a nose 17 which corre-

sponds to the noses 9 and 10 heretofore described. The nose 17 is normally maintained at the inner end of the recess 14 by means of a coiled spring 18, the respective ends of which are secured to the nose 17 and to the outer end wall of the recess 14.

In the embodiment illustrated in Figures 8 and 9 the body portion 19 is of elongated, tapered formation and is formed at its wider end with a circular opening 20 having its wall formed with a recess 21 which corresponds to the recesses 4, 6 and 14 heretofore described. The end face of the body portion 19, at the smaller end of the latter, is formed with a notch 22 for the reception therein of a tension element 23. The tension element 23 is substantially U-shape in form and one end portion 24 thereof extends along a side face of the body portion 19 and is offset at a right angle at its free end to provide a nose 25 for extension through the recess 21 formed in the wall of the opening 20.

The opposite end portion 26 of the tension element 23 extends along the opposite side face of the body portion 19 at an upward inclination and terminates at its free end in a right angularly offset hook member 27 which bears against an edge face of the body portion 19. The tension element 23 is formed of resilient material and normally maintains the nose 25 at the inner end of the recess 21. The end portion 24 of the tension element is flattened as indicated at 28 to provide such end portion with increased resiliency.

In the operation of the embodiment of my invention illustrated in Figures 1 to 5, the body portion is applied to an object such as a nut 29 with the latter extending through the opening 2 when it is desired to rotate the object in a clock-wise direction. By swinging the opposite end of the body portion in an arc in a clock-wise direction the nose 9 is wedged between the wall of the recess 4 and the periphery of the object 29 to frictionally engage the latter. Upon swinging the opposite end of the body portion in a counter-clock-wise direction, the nose 9 will be moved longitudinally of the recess 4 against the tension of the element 8 whereby the body portion will be permitted to turn relative to the object 29. If it is desired to rotate the object 29 in a counter-clock-wise direction, the body portion 1 may be inverted or may be applied to the object with the latter extending through the opening 3. Preferably the openings 2 and 3 will be of different diameters in order to adapt the wrench for use in connection with objects of different sizes.

In the embodiments illustrated in Figures 6 to 9 the operation is the same as above described when it is desired to rotate an object in a clock-wise direction. When it is desired to rotate the object in a counter-clock-wise direction the body portions 12 and 19 respectively are inverted.

It is thought that the many advantages of a wrench in accordance with this invention will be readily apparent, and although the wrench will preferably be constructed in accordance with the embodiments herein illustrated and described, it is to be understood that various changes in the details of construction may be resorted to, so long as such changes fall within the scope of the invention as defined in the appended claim.

What I claim is:

A wrench comprising, a body portion formed adjacent one end with a circular opening, the wall of said opening being formed with an elongated recess decreasing in width from one end to the other, and an elongated, resilient element fixedly secured at one end to the body portion and having its other end formed with a nose extending through said recess and projecting into said opening, said element being under a lateral tension to normally maintain the nose at the narrower end of the recess and further being circular in cross section and having a portion of its length flattened to provide such portion with relatively wide and narrow dimensions extending at right angles to each other, said relatively narrow dimension extending in the direction of travel of the nose to increase the operative resiliency of the element.

In testimony whereof, I affix my signature hereto.

ARTHUR J. LAYHON.
